UNITED STATES PATENT OFFICE.

ALBERT M. PIGEON, OF PHILADELPHIA, PENNSYLVANIA, ASSIGNOR TO PIGEON
MACHINE COMPANY, OF PHILADELPHIA, PENNSYLVANIA, A CORPORATION
OF PENNSYLVANIA.

CIRCULAR-KNITTING MACHINE.

1,266,044.

Specification of Letters Patent. Patented May 14, 1918.

Application filed June 19, 1911. Serial No. 633,938.

To all whom it may concern:

Be it known that I, ALBERT M. PIGEON, of Philadelphia, in the county of Philadelphia and State of Pennsylvania, have invented certain new and useful Improvements in Circular - Knitting Machines, whereof the following is a specification, reference being had to the accompanying drawings.

10 The invention relates more especially to knitting machines of the cylinder type wherein the cylinder may be rotated for circular knitting or oscillated at certain intervals if desired.

15 An object of the invention is to provide a needle cylinder with spring beard needles which may be placed very close together and which needles are so constructed that the yarn may reeve through the hook ends thereof whereby the needles may be moved in succession beneath the fabric supporting bed for drawing off fabric loops and whereby the position of the fabric bed may be varied relative to the working position of 25 the needles for fashioning the knitted article.

A further object of the invention consists in providing the spring beard needles with 30 yarn supporters which are so constructed that the yarn extends straight along the shanks of the needles without in any way being bent by the supporters and which supporters operate to hold the yarn at a proper distance above the point of closing the 35 beards of the needles so that sufficient time is allowed for the placing of the yarn underneath the beards of the needles before said beards are closed.

40 A further object of the invention is to provide a yarn supporter which may be adjusted for varying the height of the yarn held by the supporter on the needle shank.

45 A further object of the invention is to provide individual yarn supporters for each needle with inclined forward ends, which yarn supporters are moved radially of the cylinder so that the yarn may be supported and positively forced underneath the beards of the needles, the inclined forward ends of 50 the supporters being so disposed that the successive retracted supporter between the knitting point and the yarn feed forms a V-shaped channel for the thread.

A further object of the invention is to provide a needle cylinder with stitch cams 55 and a yarn feed which are relatively so disposed that the yarn extending from the knitting point to the yarn feed is drawn against the shanks of the needles.

A further object of the invention is to 60 provide improved devices for raising and lowering the needle cylinder so that the size of the needle loop may be varied to fashion the article and that the fabric loops may be adjusted and so that the size of the fabric 65 loops in one part of the knitted article may be varied without changing those in other parts of the knitted article.

A further object of the invention is to provide an improved means for oscillating 70 and rotating the needle cylinder whereby the parts may be operated at high speed and may be quickly shifted from oscillating to rotating movement; and whereby all possibility of lost motion is avoided during the 75 oscillation of the needle cylinder.

A further object of the invention is to provide devices for controlling the pickers so that the widening of the stocking may be commenced on the same side of the knitted 80 pocket as the narrowing thereof, so that a uniform knitted pocket is formed.

These and other objects will in part be obvious and will in part be hereinafter more 85 fully described.

In the drawings which show by way of illustration one embodiment of the invention, Figure I, is a side view of a knitting machine embodying my improvements.

Fig. II, is a similar view of the opposite 90 side of the machine.

Fig. III, is a partial end elevation looking from the left of Fig. I, showing the clutch shifting mechanism and the belt shifter, together with the pattern controlled parts for 95 operating the same.

Fig. IV, is a plan view of the supporting shelf, the needle cylinder and the yarn feeding devices.

Fig. V, is a vertical sectional view of the 100 upper part of the knitting machine, taken on the line V, V, in Fig. IV.

Fig. VI, is a plan sectional view through the needle cylinder taken on the line VI, VI, in Fig. V, showing the pickers and the raising and depressing cams. 105

Fig. VII, is a partial vertical sectional view from front to rear through the supporting frame showing the main shaft, the pattern shaft and the gears and segments 5 for operating the needle cylinder and the pattern shaft.

Fig. VIII, is a partial vertical section taken on the lines VIII, VIII, in Figs. I, and II, transversely through the supporting 10 frame and through the bearings for the main shaft and the pattern shaft.

Fig. IX, is a plan sectional view taken on the lines IX, IX, in Figs. I, and II, showing in plan the operating gears for the 15 needle cylinder, the bracket for supporting the needle bed and the fabric cage.

Fig. X, is a partial horizontal sectional view on the lines X, X, in Figs. I, II, and III, showing the transverse shaft for supporting the pattern members in plan. 20

Fig. XI, is a detail showing the pawling ratchet and the connecting lugs between the same and the shifting drum for the clutch shifting lever.

Fig. XII, is a detail view showing the pattern cam for controlling the reinforcing 25 yarn.

Fig. XIII, is a detail view showing the pattern chain and the supporting parts there- 30 for.

Fig. XIV, is a development of the cam ring showing diagrammatically the stitch cams, the pickers, the raising and depressing cams, the beard depressor cams and the yarn 35 feed.

Fig. XV, is a detail view of the upper end of the fabric cage showing the take up rolls for the fabric and the manner of operating the same.

Fig. XVI, is an end view of the shifting drum for the clutch lever, looking from the 40 left of Fig. VII.

Fig. XVII, is a detail view in section on the line XVII, XVII, in Fig. II, showing 45 the pattern wheel and the coöperating fingers for raising and lowering the needle cylinder.

Fig. XVIII, is a sectional view on the line XVIII, XVIII, in Fig. XVII, through 50 the support for the fingers, for raising and lowering the needle cylinder.

Fig. XIX, is a detail view showing the cam for raising and lowering the bed upon which the needle cylinder is supported.

Fig. XX, is a detail view showing the latch for holding the widening picker in in- 55 operative position.

Fig. XXI, is a detail view showing in inverted plan the cams for operating the 60 yarn supporting members.

Fig. XXII, is a diagrammatic view showing the needles, the yarn feed, the knitting point and the yarn supporters, the parts being shown in positions typical of continu- 65 ous rotary knitting.

Fig. XXIII, is a diagrammatic view showing in plan the yarn feed and the needle cylinder.

Fig. XXIV, is an enlarged detail view showing the needle, the yarn supporter, and 70 the beard depressor with the needle raised.

Fig. XXV, is a similar view showing the yarn placed underneath the beard of the needle and the beard closed by the depressor.

Fig. XXVI, is a similar view showing the 75 yarn supporter partially withdrawn to release the yarn for the downward movement of the needle.

In the present embodiment of the invention, the machine consists generally in a 80 needle cylinder, which is provided with a plurality of spring beard needles, the beards of which are depressed by suitable beard de- pressors, at the proper time to shed the yarn loops therefrom. The yarn is fed to the 85 needles by a yarn feed which includes a reinforcing yarn guide so that the heel and toe pockets may be suitably reinforced. The yarn feed is so disposed relative to the needle cylinder and the knitting point that the 90 yarn leading from the feed to the knitting point is pressed against the shanks of the needles. To aid in positioning the yarn for the needles, and in carrying the same underneath the beards of the needles, a yarn sup- 95 porter is provided for each needle, which properly holds the yarn relative to the beard depressors, so that the yarn may be introduced underneath the beard before the beard is depressed to shed the needle loop. The 100 drawing off of the yarn is accomplished by the movement of the needles beneath the supporting bed or ledge for the fabric, the hook of the needles being so shaped as to allow a free movement of the yarn for this 105 purpose. The fashioning of the stocking is accomplished by controlling the movement of the needle cylinder so as to change the distance the needles are drawn beneath the fabric supporting bed. The needle cylinder 110 comprises two series of needles, one of which may be rendered idle during the knitting of the heel and toe pocket.

The pickers for widening and narrowing are so controlled that the leading needles of 115 the active series are thrown in on the same side for widening as were thrown out for narrowing, whereby an even and uniform heel and toe pocket is produced. A sup- 120 porting cage is provided for receiving the knitted product, and a take-up is located adjacent the upper end of the cage, which not only assists in taking the fabric from the needles as it is knitted, but also in pack- 125 ing the knitted product in the cage.

During the rotation of the needle cylinder, the cage rotates therewith, and through its rotary action, the take-up rolls are operated. All of the parts above noted are controlled 130 by pattern mechanism, whereby a complete

stocking may be produced and fashioned automatically.

Frame structure.

5 Describing the machine more in detail and with special reference to the drawings, said machine consists of a main frame 1, which is supported on suitable legs or standards 2. Said main frame is box like in structure and 10 carries a supporting shelf 3, at its upper end. This supporting shelf projects forwardly toward the front of the machine and the needle cylinder 4, is located in said forwardly projecting portion. The parts of 15 the machine are operated by the main shaft 5, which extends transversely through the supporting frame 1. It will be noted as more clearly shown in Fig. I, that the needle cylinder is directly in front of the operating parts, for controlling the same, and the various members coöperating with the needles. By this relation of the needle cylinder to the frame and operating parts, I 20 am able to provide a machine which is very compact and takes up comparatively little room from one side to the other side, so that a series of machines may be placed side by side and occupy a minimum amount of 25 floor space.

30 *Needle cylinder and needles.*

The needle cylinder 4, extends through an opening 5^a, in the supporting shelf 3, and is entirely free from said shelf so that said 35 needle cylinder may be raised and lowered relative to said shelf. The needle cylinder at its lower end is attached to a gear 6, by suitable screws 7, (see Fig. V). The gear 6, rests upon the upper face of a supporting bed 8, which through said gear, supports the needle cylinder. The supporting bed 8, is mounted on a bracket arm 9, carried by a standard 10, (see Fig. II). The standard 10, is supported by suitably 40 spaced brackets 11, and is free to move up and down therein. The needle cylinder is provided with a series of spaced ribs forming needle slots in each of which is mounted a needle jack 12, carrying the needle 13.

50 The needle jack 12, is of substantially the same width as the ribs on the needle cylinder. This jack is also in thickness substantially the same as the width of the needle slot or the distance between two adjacent 55 ribs on the cylinder, so that when the jacks are in place the cylinder at this point is substantially one solid band. This not only strengthens the cylinder and allows a very small cylinder to be made with narrow ribs, 60 so that the needles may be placed very close together, but the comparatively large surface of the jack relative to the usual needle formed with an integral butt, gives a much more efficient wearing surface and lubricating 65 surface for the needle supporting parts.

The needle 13, as clearly shown in Fig. V, is bent outwardly over the upper end of the jack; and extends along the front of the jack. The needles are held in their jacks and in the needle cylinder by flexible bands 70 16. The jack is held in place at its upper end by the needle, while the lower end of the jack is held in place by the cam ring and stitch cams. This manner of holding the jack in the needle slot avoids the use of 75 extra flexible bands for the jack and allows the jack and needles to be shortened so that a very short needle cylinder may be used. The upper or hook end of the needle as 80 clearly shown in Figs. XXIV, and XXVI, is made comparatively wide at its extreme upper part 17. The purpose of this particular shaping of needles is to allow the yarn engaged by the needle to move freely through the hook of the needle and the 85 needle to draw off the yarn for the stitch, as will be hereinafter more fully described.

Needle cylinder operating means.

The needle cylinder is supported, as above 90 noted, so as to move freely up and down in the opening in the shelf 3. In order that the machine may have the capacity of knitting stockings, the cylinder is provided with mechanism whereby the same may be rotated 95 at intervals and may be oscillated at intervals. The needle cylinder is rotated and oscillated by a gear 18, which gear is secured to a bevel gear 19, by screws 20, (see Fig. V). The gear 19, is rigidly attached to a 100 vertical shaft 21, which is mounted to rotate in a vertical bearing 22. The shaft 21, is secured at its upper end to a collar 23, by a set screw. The hardened metal plate 24, is fastened to the upper end of the shaft 21, by a screw 25. This hardened metal plate 24, rests on the upper end of the collar 23. The collar 23, serves as the bearing for supporting the vertical shaft 21, and holding the same properly seated in the bearing 110 sleeve 22. Any wear may be taken up by loosening the collar 23, and turning the screw 25, which will raise the shaft 21, in the bearing sleeve 22, after which the collar 23, is again readily connected to the shaft. 115 The bearing sleeve 22, extends through the opening 26, in the shelf 3, and is mounted on suitable brackets or lugs carried by said shelf. The gear 18, is considerably wider than the gear 6, which is attached to the 120 lower end of the cylinder 4, so that the cylinder 4, may be raised and lowered without moving the gear 6, out of operative connection with the gear 18, which has no lateral or vertical movement. The bevel gear 19, on the lower end of the vertical shaft 21, meshes with the bevel 27, which is integrally formed with sleeve 28, fixed on the central or driving shaft 5. The fast driving pulley 30, is attached to a sleeve 31, mounted 125 130

to rotate freely on the shaft 5. At its inner end, the sleeve 31, carries the pinion 32, which meshes with a gear wheel 33, on the countershaft 34. A gear wheel 35, is rigidly secured to the gear wheel 33, and rotates freely on the countershaft. This gear wheel 35, meshes with a pinion 36, on a second sleeve 37, which rotates freely on the first named sleeve 31. This second sleeve 37, is rigidly connected to the slow speed driving pulley 38.

A loose pulley 39 is mounted to rotate freely on the outer sleeve 37. The two sleeves 31, and 37, and the shaft 5, are all mounted in a suitable bearing 40. The shaft 5, at its other end is mounted in a bearing 41. The bearings 40, and 41, are secured to the main frame. A pinion 42, is loosely mounted on the shaft 5, and gears with the segment gear 43, which is pivoted to swing about the supporting axis 45. The segmental gear 43, is connected by a link 46, to a stud 47, secured to the outer face of the gear wheel 33. This stud 47, may be readily adjusted on the gear wheel to vary the stroke of the segment. The stud in effect forms a crank arm which, as the gear wheel rotates, oscillates the segment back and forth about its axis 45, and in turn rotates the pinion 42. The sleeve 28, carrying the bevel gear 27, may be clutched either to the pinion 42, or to the pinion 32, by a clutch pin 50, which as herein shown, is mounted to slide in the sleeve 28, and is formed with tapered outer ends. The pinion 42, has a tapered socket 51, adapted to receive the tapered end of the clutch pin 50, and the pinion 32, has a similar socket 52, adapted to receive the other tapered end of the clutch pin. A clutch sleeve 53, surrounds the sleeve 28, and the screw 55, extends through the clutch sleeve 53, and through a slot in the sleeve 28, and is connected to the clutch pin 50, so that as the clutch sleeve 53, is shifted to the right, the pinion 32, will be locked to the sleeve 28, and through the gears 27, 19, and 18, any rotation given to the pinion 32, will be conveyed to the cylinder. Inasmuch as the pinion 32, is connected directly to the fast pulley 30, through the sleeve 31, when the clutch pin is in the position shown in Fig. VIII, the cylinder will be rotated through the parts named. When the clutch pin is shifted to the extreme left, so as to connect the pinion 42, to the sleeve 28, then the pinion 32, will be free from the sleeve 28, and as this pinion rotates, the gear 33, will be rotated, which in turn through the crank pin or stud 47, will oscillate the segmental gear 43, and in turn rotate the pinion 42, and, as the segment oscillates first one way and then the other, the pinion 42, will be rotated first in one direction and then in the other. This rotation of the pinion 42, in reverse directions will through the sleeve 28, to which it is then

connected, the bevel gear 27, the bevel gear 19, and the gears 18, and 6, oscillate the cylinder. This oscillating of the cylinder through the gear 33, is at high speed. If the pulley 38, is the active driving pulley then the pinion 36, will rotate the gear wheel 35, which is larger in diameter than the gear wheel 33, and will thereby cause the segmental gear to oscillate at a slower speed than when the gear wheel 33, is driven through the pinion 32, and its connection with the high speed pulley 30.

Clutch shifting and speed changing mechanism.

As a means for shifting the clutch so as to cause the cylinder to rotate or to oscillate, as desired, I have provided a clutch shifting lever 60, (see Figs. III, and IX). A rod 61, is mounted to reciprocate longitudinally in the supporting frame 1, and said rod is provided with a sleeve 62, which carries a fork arm 63, adapted to engage the groove 65, between the collars on the clutch shifting sleeve 53, so that when the rod 61, is moved in one direction, the clutch sleeve will be carried therewith, and when said rod is moved in the other direction, the clutch sleeve will be given a reverse movement. A second collar 66, is carried by the rod 61, and is formed with a lug 67. This lug 67, lies between the forked arms 68, and 69, carried by the upper end of the clutch shifting lever 60. The arm 68, is provided with a screw 70, while the arm 69, is provided with a screw 71. These screws are so positioned, that there is a slight lost motion between the clutch shifting lever 60, and the lug 67. In the manipulation of the clutch pin, it is desired that said pin should be moved far enough to seat firmly in the tapered socket in the part which it engages, but any further movement of the clutch pin would cause a binding of the pinion against its bearing, and, if the clutch pin is not moved far enough to be properly seated, then there is a lost motion between the driving parts.

In order to adjust the shifting lever to the proper nicety to seat the clutch pin properly in its receiving pocket, the screws 70, and 71, may be adjusted, if the throw of the clutch pin to the right as viewed in Fig VIII, is not sufficient, to take up the lost motion, then the screws 70, may be turned so as to cause a further throw to the clutch pin. The other adjustments of these screws in order to properly position the clutch pin will be obvious.

The shifting lever 60, is controlled by a clutch drum 72, mounted on a cross shaft 73, journaled in suitable bearings in the frame 1. This clutch drum is made up of a cylinder having outer ribs and cam blocks 74, which are properly positioned on the outer face of the drum to form a cam recess, which receives a roller carried by the

lower end of the shifting lever 60. By the proper rotating of the clutch drum 72, the lever 60, may be shifted so as to control the clutch and cause the cylinder to rotate during the proper interval for circular knitting and to cause the cylinder to oscillate during the proper interval for forming a heel or toe pocket.

This clutch drum 72, is freely mounted on the shaft 73, and a pawling ratchet 75, is connected to the shaft 73, by a set screw. This pawling ratchet carries a laterally projecting lug 76, and a similar lug 77, is formed on the drum. An adjusting screw 78, extends through the lug 77, and may be held in adjusted position by a set screw or any other desired means. By this construction, the pawling ratchet is set on the shaft and the drum may be adjusted relative to the pawling ratchet, by adjusting the screw 78. This adjustment aids, in assembling of the parts to properly position the shifting drum 72, so as to bring its cam shoulders into action in the proper timed relation to the other parts of the machine. This adjustment provides a means for taking up any wear in the cam plates 74, and also takes strain of clutching from the screws in the pawling ratchet and clutch drum.

As a means for shifting the belt from the fast pulley to, the slow pulley, I have provided a belt shifting lever 80, which is pivoted at 81, to a rod 82, freely mounted in suitable bearings on the side frame of the machine, see Fig. I. This belt shifting lever 80, is formed with projecting fingers 83, between which the belt passes. By shifting the lever 80, the belt will be shifted from one pulley to the other.

The arm 85, is fixedly mounted on the rod 82, and is moved by the spring 86, so that the bearing lug 87, carried by the arm 85, is held against a shifting cam 88. As the cam 88 rotates, the cam shoulders thereon will move the arm 85, away from the frame, or allow the same to be moved toward the frame of the machine through the action of the spring 86. The latch 90, is pivoted to the other end of the arm 85, and said latch is formed with a notch 91, adapted to engage a pin on the back side of the belt shifting lever 80. A handle 92, is provided for manually releasing the latch 90. A spring 95, is connected to one of the arms 83, and to the frame of the machine, and this spring normally tends to throw the belt to the loose pulley when released by lifting the latch 90. When the latch is in engagement with the pin on the belt shifting lever 80, said lever will then be controlled by the shifting cam 88. The shifting cam 88, is rigidly attached to the outer end of the shaft 73, and this shaft is controlled by a pattern mechanism to be hereinafter described.

Stitch cams.

The needles are raised and lowered during the normal knitting action by stitch cams which engage the butts 14, of the 70 needle jacks. These stitch cams are secured to a cam ring 100, see Fig. XIV. The stitch cams are composed of suitable blocks 101, and 102, which are so positioned as to form a cam groove to receive the needle butts, 75 and to thereby raise and lower the needles. I have shown herein two stitch cams, both of which are in action during the oscillation of the cylinder, so that one of them effectively engages the needle butts when 80 the cylinder oscillates in one direction and the other engages the needle butts when the cylinder oscillates in the opposite direction. The right hand stitch cam as shown in Fig. XIV, is the only operative cam during the rotation of the needle cylinder. In order to render the stitch cams 101, and 102, effective or ineffective, I have provided switch cams 103, and 104, respectively, which are pivoted in suitable brackets carried by 90 the supporting shelf 3, these switch cams are spring-pressed, whereby they are normally held in contact with the edges of their respective cams 101, and 102. If the needle cylinder is rotating in the direction of the 95 arrow shown in this figure, then the switch cam 103, will be ineffective, and will ride lightly on the butts of the needles, while the switch cam 104, shown at the right, will engage the needle butts and carry the same 100 down into the main stitch cam.

During the oscillation of the cylinder, the long butt needles on one series of the needles will have been positioned entirely above the stitch cams as will be hereinafter more fully 105 described.

Yarn feed.

The yarn feed as herein shown, consists of a yarn feeding loop 105, which is rigidly 110 secured to a bracket arm 106, mounted on the rod 107, secured in suitable brackets 108, on the supporting frame or shelf 3, at the upper side of the main frame. This rod 107, is capable of being oscillated in its supporting bracket to move the yarn feed out of operative position. During the entire action of the machine, the yarn feed is in fixed position, and is located close to the needles and directly over the yarn supports. The stitch cams are so located relative to the yarn feed that the knitting point indicated at 109, in Fig. XIV, is in advance of the yarn feed. Said knitting point is also in advance of the tangential point of a 125 line passing through the yarn feed and touching the needle cylinder, so that the yarn extending from the knitting point to the yarn feed will be thrown snugly against the shanks of the needles.

Beard depressors.

Each needle is provided with a beard depressor 110, which is mounted in the needle slot directly over the needle jack. The depressors also extend between the fabric supporting members and the active edge is enlarged to fill the entire space between said members, so that the beard of the needle will be engaged by the depressor with certainty.

The upper end of the beard depressors is formed so as to engage and depress the beard of the needle and allow the loop on the needle shank to be shed over the spring beard. The beard depressors are each formed with a butt adapted to engage operating cams 111, see Fig. XIV. These operating cams 111, are carried by a member supported from the cam ring 112. The cam ring 112, rests on the ring 113, which is secured to the upper end of the needle cylinder. Said cam ring 112, is held stationary by the posts 115, which are mounted on the supporting shelf 3. Screws 116, engage each side of the posts 115, and serve as a means for angularly adjusting the ring 112, relative to the thread feed. The rings 112, and 113, move vertically with the needle cylinder, and the ring 113, rotates therewith. As a means for securing the ring 113, to the needle cylinder, I have provided a brass ring 117, see Fig. V, which is seated in the inner face of the ring 113, and is clamped against the ribs of the needle cylinder 4, by screws 118. This provides a means for firmly clamping the supporting ring 113, to the needle cylinder without injury to the cylinder ribs or the binding of the needles or depressors. The supporting ring 112, may be adjusted diametrically to the needle cylinder by screws 119; this allows for the taking up of any wear between the parts and the centering of the supporting ring relative to the rotating cylinder.

The depressors for the spring beards of the needles and the operating mechanism therefor form no part of the present invention, but are shown, described and claimed in my prior Letters Patent of the United States No. 943,230, dated December 14th, 1909.

Fabric depressors and yarn supporters.

In my present machine I do not use strictly speaking, any sinkers for positioning the yarn about the shanks of the needles. The position of the yarn feed relative to the knitting point draws the yarn tangentially against the shank of the needles and serves one function of the sinkers. The downward movement of the needles below the fabric supporting bed draws off the yarn for the stitch and serves the other

function of the usual sinkers. I do however, use a fabric depressor for holding the finished fabric during the ascent of the needle and also a yarn supporter for holding the yarn a sufficient distance above the fabric depressors to allow the action of the beard depressors. Said fabric depressors and yarn supporters as herein shown, consist of a series of sliding members 120, which are shaped and constructed in the manner similar to the usual sinkers. A sliding member is provided for each needle, and is mounted so as to move radially of the needle cylinder. Said fabric depressors are mounted to slide in grooves formed in the supporting ring 113, and are moved back and forth by cams 121, carried by the lower side of the supporting ring 112. These cams 121, are shown in Figs. IV, and XXI, and are so constructed as to move the fabric depressors back and forth in the proper time relations to the needles at the point of stitch formation. Said members are withdrawn at the knitting points, by the cam inclines 121^a, (see Fig. XXI, and dotted lines in Fig. IV), to an extent just sufficient to allow the needle loops to be carried down past the ends of the supporters, and are again thrown inward by the cam inclines shown at 125^b. In oscillatory knitting, on the return movement, the partial withdrawal of the yarn supporters by the cam inclines 121^a, again occurs, but the yarn supporters are immediately thrown inward again by the cam inclines at 125^a. Said fabric depressors are also withdrawn at a point central of the stitch cam, or opposite the yarn feed by the cam incline at 121, so that during the reversal of the movement of the cylinder, during the oscillating of the same, the yarn is released from around the end of the fabric depressors, as is usual in connection with the withdrawal of the web holders in ordinary latch needle knitting. The yarn supporters are however, moved inward between the point directly opposite the feeding of the yarn and the knitting point by one or the other of the cam inclines 125^c, according to the direction of motion, in order to support the yarn as above noted. During oscillatory knitting, (as for heel and toe gores), the yarn leads up from the selvage loop of the fabric, passes partly around the shank of a needle at or near the dividing line between the active and the idle needles, and thence leads to the yarn guide.

If, in moving toward the knitting point, the yarn at the region of the then leading active needle is not supported at the proper height, before the beard closing action occurs, it may be penetrated by the beard when the needle descends, or may be entirely missed. Hence it is essential that before the closure of the beard of the leading

needle of the active series, a yarn supporter shall be in operative position, at a point sufficiently close to the leading needle, to insure the support of the yarn for proper engagement by that needle, and for the safe closing of the beard thereof.

In the embodiment of my invention shown in the drawings, (where the yarn supporters are withdrawn completely in 10 passing the yarn guide), the reinsertion of the yarn supporters, is effected by one or the other of the cam inclines 125°, and will take place before the leading needle reaches the point where closure of its beard commences.

15 At the inner end each fabric depressor is formed with the usual radially extending surface 120° which forms the fabric bed or supporting ledge. Each fabric depressor and yarn supporter is provided with an inwardly projecting nose 122, which is spaced a short distance above the supporting bed for the fabric, in order that the nose may extend over the loops of the knitted fabric, and hold the same down on the supporting bed. 25 The upper edge of the yarn supporter is as herein shown, inclined as at 123, see Figs. XXIV to XXVI. When these yarn supporters are moved forward, the yarn extending from the knitting point to the yarn feed will rest on the inclined shoulder and said inclination will assist in directing the yarn toward the shank of the needle. Inasmuch as these yarn supporters from a 30 point adjacent the yarn feed toward the knitting point are projected inwardly gradually, a lesser distance, a downwardly inclined channel is formed which extends in the general direction of the knitting wave, and thus forms a substantially straight path 35 for the yarn from the knitting point to the yarn feed.

This yarn supporter positively holds the yarn well up on the shank of the needle and separates the same from the fabric supporting bed so as to give plenty of time for the closing of the beards of the needle after the yarn has been introduced underneath said spring beard.

In order that the distance which the 50 thread is held on the shank of the needle above the supporting bed, may be adjusted, I have provided for the adjustment of the cam which operates the yarn supporting parts. This cam as shown in Figs. IV, and 55 XXI, consists of a plate 125, which is secured to the supporting ring 112, by screws 126, these screws extending through slots in the supporting member. Adjusting screws 127, may be attached to the ring 112, for 60 adjusting the cam plate 125, so as to regulate to a nicety the amount of inward movement of the yarn supporters. It will readily be seen that if said supporters are moved in a greater distance toward the center of the cylinder, that the inclined shoul-

der 123, will raise the point of contact between the yarn and the shank of the needle. On the other hand, if the cam plate is adjusted in the opposite direction, this point of support of the yarn on the needle shank 70 may be lowered. The radial projection of the summit of the cam inclines at 121°, (which correspond to the knitting points), is such as to withdraw the yarn supporter only to an extent sufficient to permit the 75 yarn to be snapped down past the tip or nose of the yarn supporter by the needles in their descent.

This position of the parts is shown in Fig. XXVI, where it will be seen that the 80 yarn supporter is only partially withdrawn, so that its nose still extends slightly inward beyond the outer face of the adjacent needle. Such partial withdrawal permits the yarn to be snapped down by the 85 descent of the needle, without undue strain, and at the same time preserves such relative position of the yarn supporter and needle as to minimize the danger of trapping the yarn during oscillatory knitting, 90 since the yarn leading up from the selvage loop is supported and divided from the fabric at a point close to where it turns about a needle shank, and hence, after passing the knitting point, lies on top of the 95 supporters, throughout the remainder of the stroke, and also on the return stroke.

It will be noted that the summit of the cam incline 121, is at a greater radial distance from the center of the cylinder than 100 the summit of the cam incline 121°.

The result of this arrangement is that if any yarn shall by accident have been trapped by the yarn supporter and needle shank at the region of the selvage loop, it 105 will be disengaged by the complete withdrawal of the yarn supporter at the time it passes the yarn guide.

The avoidance of trapping above referred to is a danger which obviously occurs only 110 in oscillatory knitting, and hence, if the machine is intended to be used for continuous rotary knitting alone, the yarn supporters may be withdrawn entirely clear of the needles at the knitting point.

It will be obvious however, from certain aspects of the invention this supporting shoulder for the yarn need not necessarily be inclined for the reason that during the operation of the machine, the essential feature is the supporting of the yarn a sufficient distance from the fabric bed to allow the operation of the beard depressors as the relative position of the yarn feed to the knitting point will draw the yarn against the 125 shank of the needles as above noted.

The extreme inner ends of the yarn supporters as noted, are on a sharper incline in order to terminate the inner nose of the yarn supporter, in order to make a rela- 130

tively short nose, so that as soon as the yarn supporter is withdrawn the yarn may be quickly released to allow the same to be carried down to the knitting point.

- 5 By this arrangement of yarn supporter, and by the combination therewith of means for effecting relative movement in a radial direction between the needle and the yarn supporter, I am able during oscillatory 10 knitting to positively uphold the yarn in a proper position to be passed by the beards of the needles, before they are closed, by the beard depressors, and at the same time, the yarn is not positively held against the 15 shank of the needles, so that in the oscillation of the needle cylinder, during the formation of the heel and toe pockets, the yarn may be crowded upward on the yarn supporters by the shanks of the idle needles, 20 and all interlocking of the yarn by the idle needles is avoided. I am therefore by this construction able to use a relatively fixed yarn feed and do away entirely with the movements of the yarn feed toward and 25 away from the needle cylinder and toward and away from the idle needles during the oscillation of the cylinder. Furthermore, the yarn is not bent about the shank of each needle as with the use of sinkers and therefore 30 no objectionable loose yarn is drawn off as the idle needles pass the knitting point.

Pickers and raising and depressing cams.

- 35 During the formation of the heel and toe pockets, it is necessary to provide means for rendering the long butt needles idle, and for operating in succession upon the active needles to throw out in succession the leading 40 needles of the series for the purpose of narrowing the heel and toe pockets and to throw in the leading needles in pairs in the well known way for widening the heel and toe pockets. In order that the long butt 45 needles may be raised to an idle level I have provided a raising cam 130. This cam is carried by an arm extending from a collar 131, mounted on a vertical stud attached to the supporting shelf of the machine. A 50 depressing cam 132, for returning the idle needles into action when circular knitting is to be produced, is attached to a second arm, on the collar 131. These arms extend in opposite directions from the supporting 55 stud, so that when one cam is thrown into action, the other cam is thrown out of action. A rod 133, is pivotally secured to one of the arms of the collar 131, and said rod projects through an arm 135 supported on the outer end of the rod 61, which shifts the clutch in changing from 60 circular knitting to oscillatory knitting. A spring 136, encircles the rod 133, and at its outer end bears against the arm 135. A 65 collar 137, is rigidly attached to a rod 133.

A collar 138, at the outer end of the rod 133, forms an abutment for the other end of the spring 136. When, therefore, the clutch shifting mechanism is moved so as to shift the clutch for circular knitting, the cam 132, will be thrown into action so as to engage the long butts of the idle needles, and move the same down into active position. When the clutch is shifted in the opposite direction, so as to cause the needle cylinder to oscillate, the cam 130, will be moved into the path of the long butt needles, which will raise the same to an idle level.

In order to throw out the leading needles in the active series, first on one side and then on the other as the cylinder oscillates, I have provided pickers 140, which, as herein shown, are pivoted to brackets mounted on the supporting shelf of the machine. The pivotal support for each picker is inclined, so that as a needle butt is brought into engagement with a picker, the picker will be oscillated about its axis, and the swinging of the picker will raise the needle jack in the needle cylinder and carry the needle to an idle position. Each picker is formed with a separate detachable finger 141. This finger has a ledge 142, on to which the butt of the needle or the needle jack is carried by the movement of the cylinder. The butt of the needle jack, as clearly shown in Fig. V, is formed with a square shoulder, and as the picker is raised, this shoulder will slide along the ledge 142, until the picker is raised sufficiently to slide underneath the butt of the needle jack. The extreme upper corner of the picker finger is chamfered in order to allow the butt of the needle jack to pass over the same. By this construction of picker I am able to carry a needle jack and needle from the extreme lower position or active level to the extreme upper position or idle level, without the coöperation of any auxiliary cams or lifting means.

As a means for depressing the needles two by two in order to widen the heel and toe pockets, I have provided a widening picker 150. This widening picker is connected by universal joints and limiting stops to a supporting bracket 151. In Fig. VI, the widening picker is thrown into inactive position, and is held in said inactive position by the arm 152. When this picker is released by the movement of the arm 152, it will move to a radial position directly in front of the supporting bracket 151, therefor. As the needle butts are brought into contact with said widening picker, two needle butts will engage the same, and as the cylinder rotates, this picker will carry the two butts downward to an active level. When the cylinder is moved in one direction the widening picker operates to carry down the two leading needles of one side of the active series, and when

the cylinder is moved in the opposite direction, the picker operates to carry down the two leading needles on the other side of the active series of needles. In order that the 5 picker on the left of the machine for throwing out the needles may be rendered ineffective during circular knitting, I have formed the arm which supports the cam 132, with a projection 153, which engages a stud on the picker support, and raises the same when the depressing cam 132, is thrown into action. This moves the picker 141, entirely out of action. The picker at the other side of the needle cylinder is in 10 active position, but will be ineffective for the reason that the cylinder continues to rotate in such direction that the needle butts are not brought into engagement with the picker. The picker construction shown and 15 described herein forms a part of my Patent No. 1,213,003 dated January 16, 1917, and will not need further description in this connection, but has been merely described and illustrated in the preferred form of 20 picker to be used in connection with my machine.

The manner of controlling the pickers so as to render the same effective and ineffective, is, however, a part of the present invention. The clutch shifting mechanism is so operated that when the clutch is shifted to cause the cylinder to oscillate, the picker on the right hand side of the machine will be the first picker to be effective, and to throw out 30 of action the leading needle of the active series. This is due to the fact that the picker comes into action upon the first reverse movement of the cylinder. In order that the stocking may be perfect and uniform, 35 it is essential that the needles on the same side of the active series, which are first thrown out of action, shall be the first to be thrown into action. In order to accomplish this throwing in of the widening picker, 40 I have formed the clutch drum with pins 155, which come into engagement with a cam lug 157, on an arm 158, (see Figs. I, and XI), which arm is pivoted to the lower 45 end of a lever 160, pivoted at 161, to the side of the main frame, and said lever carries an arm 162, which in turn engages the lower end of the depending portion of the 50 lever 152.

The lever 152, is mounted on a bracket 55 165, pivoted at 166, to the lower side of the supporting shelf. The arm 158, at its outer end is formed with an adjustable hooked finger 167, which is normally positioned just below the path of movement of a pin 60 168, attached to a collar on the shaft supporting and oscillating with the segment gear. When a pin on the clutch drum engages the cam lug on the arm 158, said arm will be raised so as to throw the hook carried thereby into the path of movement of

the oscillating pin. The clutch cam is moved as will be hereinafter explained by a pawl directly connected with the segment gear, and this pawl is so positioned as to be active when the segment gear is moving toward 70 the front of the machine, so that the forward movement of the segment will position the arm 158, which controls the widening picker for engagement with the pin on the collar moving with the segment gear, 75 and the backward movement of the segment gear will become operative to shift the parts to release the picker, and to allow the same to return to active position. Inasmuch as the clutch drum is moved by a forward movement of the segment, the clutching up of the parts to oscillate the cylinder necessarily becomes operative in the forward movement of the segment, and therefore, the throwing in of the narrowing 80 picker necessarily occurs in a predetermined relation to the shifting of the clutch. If the widening picker is also thrown into action by the mechanism which shifts the clutch drum on the movement thereof then 85 the widening picker would become effective to act upon the leading needles on the opposite side of the active series from that which the first narrowing picker operated upon, but by the above construction, wherein the 90 return movement of the segment throws into action the widening picker, I am able to accomplish the result above described, and produce a uniformly shaped stocking.

The finger 162, is provided with two 100 notches 170, and 171. The lever 152 is normally spring-pressed, so as to release the widening picker. The finger 162, will prevent this movement, provided the notch 170, lies in the path of the lower end of the lever 105 152. The shifting above referred to consists in moving the finger 162, so as to allow the spring to operate the lever 152. The lever 152, also lies in the path of the rod 61, which shifts the clutch, (see Fig. I). 110 The widening picker will remain in action until the clutch is shifted for circular knitting, and upon this shifting of the clutch, the rod 61, will engage the arm of the lever 152, and throw the widening picker out of 115 action. The finger 162, will shift so as to bring the notch 170, into the path of the lever 152, and hold the widening picker out of action even though the rod 61, is withdrawn from the path of movement of the 120 lever 152, by the shifting of the clutch, so as to produce an oscillation of the cylinder, for the beginning of the heel and toe pockets.

Fashioning mechanism.

125

The fashioning of the leg of the stocking is accomplished by controlling the lengths of the stitches, that is, the movement of the needles below the supporting bed or 130

ledge for the knitted fabric. The needle cylinder as above noted is carried by the standard 10. The standard 10, is formed with a collar 175. This collar has a projecting lug 176, (Fig. XIX), with a cam face on its lower side. Loosely mounted on the standard 10, is a sleeve 177, which sleeve carries an arm 178, which is provided with a series of fingers cooperating with a fashioning cam 180. The sleeve 177, also carries an adjustable pin 179. It will readily be seen that when the needle cylinder is lowered, smaller fabric loops will be drawn, and when the cylinder is raised, longer loops will be made. The fashioning cam 180, is formed with a plurality of concentric fashioning ribs, the outer faces of which, with the exception of the outer rib, lie in the same plane. The arm 178, is provided with two fingers 181, and 182, which engage the two concentric ribs 183, and 184, respectively. These concentric ribs on the fashioning cam are formed with similar cam shoulders 185. These fashioning ribs control the stitches or fabric loops during the formation of the leg, and the ankle of the stocking. The concentric rib 183, is cut away from the point 186. The finger 181, projects a greater distance from the supporting block therefor, than the finger 182, so that when the concentric ribs 183, and 184, are moved into the path of these fingers, the outer pin 181, will shift the arm 178, and position the needle cylinder in a certain predetermined relation to the knitting cams. This position of the needle cylinder is for knitting the upper portion of the leg of the stocking. The stitches will remain uniform as long as the finger 181, is on the extreme raised portion of the rib 183. When the point 186, is reached, the rib is inclined, so that the finger may gradually allow the sleeve 177, to turn, which in turn will gradually allow the needle cylinder to drop, thus gradually tightening the stitches or shortening the length of the fabric loops, during the formation of the ankle, and thereby the fashioning of the ankle is secured. This gradual shifting of the needle cylinder downward will continue until the pin 182, engages the ledge 184. The pin 182, will rest on the ledge 184, holding the cylinder in a fixed vertical position during the forming of the ankle of the stocking. A continued movement of the fashioning cam will bring the cam face 187, of the rib 188, into contact with the finger 189, which positions the cylinder for the proper formation of the stitches for the heel pocket of the stocking. A further movement of the fashioning cam will bring the cam surface 190, of the rib 191, into contact with the finger 192, which will position the needle cylinder for the proper formation of the foot of the stocking.

A further movement of the fashioning cam 65 brings the pin 189, into contact with the rib

195, to position the cylinder for the formation of the stitches in the toe pocket of the stocking. After the completion of the stocking, the rib 196, will contact with the pin 197, and position the cylinder for the formation of the stitches in the looper rounds. By making the fingers which engage the various ribs on the fashioning cam independent of each other, I may provide a separate adjusting means for each finger, which, as 75 herein shown, consists of adjusting screws for positioning the fingers and set screws for holding the fingers in adjusted positions. It will be readily seen that by the independent adjustment of these fingers, the character of 80 the stitches may be varied in the leg portion of the stocking, without varying the same in the foot of the stocking, or said stitches may be varied in any desired part of the stocking, without varying those in any 85 other part of the stocking.

By adjusting the pin 179, in the sleeve 177, the entire stitch or fabric loop length throughout the entire stocking may be adjusted, which adjustment will be carried 90 through all the various increments of adjustment secured by the adjusting of the fingers co-acting with the fashioning cam.

Fabric takeup and supporting cage.

As a means for receiving the knitted stockings I have provided a cage 200, which is preferably formed of wire meshing and is supported for rotation upon an adjustable pin 201. The upper end of the cage or basket 200, is provided with a ring 202, which engages within an opening in the lower part of the supporting bed 8, for the needle cylinder. This ring 202, freely engages the bed, and does not in any way prevent the proper vertical movement of the bed for positioning the needle cylinder to change the stitch in the different parts of the stocking. Located in the upper end of the cage is a lug 206, which normally lies in the path of a pin 205, carried by the gear, which supports the needle cylinder. As the needle cylinder rotates, said pin will engage the lug and rotate the basket or cage in unison with the needle cylinder. A second lug 115 203, engages the rear side of the pin 205, and said pin is located between the lugs 203, and 206. When the rod 61, is shifted in order to position the parts for oscillating the needle cylinder, a bracket arm 207, carried by the drum shifted clutch lever 60, engages a stud 208, carried by the lug 203, which forces the lug 203, inward out of the path of the pin 205. This lug 203, is mounted on a yielding strip, so that the same may 125 be moved as above noted. When this lug 203, is withdrawn from the path of the pin 205, the rearward movement of the pin, due to the oscillating movement of the cylinder, will merely carry the pin away from the lug 130

206, and the cage will remain idle, therefore, during the entire oscillations of the needle cylinder. Located within the upper end of the cage is a takeup mechanism consisting 5 of a ribbed takeup roll 210, which is mounted in suitable bearings in plates carried by the upper end of the cage. Coöperating with the roll 210, is a second roll 211, which, as herein shown, is formed in sections; this 10 roll is mounted in slotted bearings, so that the same may be moved toward and from the feeding roll 210. Spring fingers 212, are attached to the side of the cage at one of their ends and at their free ends encircle the 15 shaft supporting sections of the roll 211. These springs 212, normally press the roll 211, against the active feed roll 210. These springs not only serve as a means for holding the rolls in engagement but also serve as 20 a stripper for stripping the knitted web from the feeding rolls. The feeding roll 210, is provided with a plurality of annular channels, and stripper fingers 213, attached to the side of the basket, have their free ends 25 extending into said channels. These fingers serve to strip the knitted fabric from the active feed roll 210. As a means for operating the active roll 210, I have formed the same with a ratchet wheel 215. The arm 30 216, is loosely mounted on the shaft supporting the feed roll 210, and a spring 217, normally presses the said arm downward against the stop 218. A pawl 219, is pivotally mounted on the arm, and is pressed by 35 a spring 220, so that said pawl bears against the ratchet wheel 215. A locking dog 221, is spring pressed into engagement with the ratchet 215, and prevents the retrograde movement of the same. In order to lift the 40 arm 216, the stud 222, on which the pawl 219, is mounted, projects upwardly so as to engage a cam ledge 225, secured to the cylinder bed 8. As the cage is rotated with the needle cylinder, this stud 222, will ride up 45 on the cam ledge 225, raising the pawl, and as the stud moves down the cam ledge, the pawl will be thrown down by the action of the spring controlling the same, which will rotate the active feed roller. By the above 50 construction wherein the takeup rollers for the knitted fabric are located at the upper end of the supporting cage, I am able to pack the knitted goods into the cage, and a number of pairs of stockings may be knitted and placed in said cage. By this construction also, wherein the takeup rollers are at the upper end of the cage and operated by the rotating of the cage, said rollers will remain idle during the knitting of the 55 heel and toe pockets for the reason that the cage is not rotated at this time. I have formed the cage with an opening 226, adjacent its upper edge and the idle period in the movement of the cage not only affords 60 65 a means for rendering the feed movements

of the takeup mechanism idle, but allows the knitted material to be removed from the basket during this idle period if desired.

Reinforcing yarn feed.

70

In order to reinforce the heel pocket, or the toe pocket, or if desired the forming of a gartered portion at the top, I have provided a reinforcing yarn feed, which consists of a guiding tube 230. This reinforcing yarn feed is carried by the outer end of an arm 231, which is bent outwardly near its outer end and extends through a guiding opening carried by the bracket arm 106. The arm 231, is formed with a slotted portion which engages the rod 107, and a lever 232, operates to force the arm 231, forward and hold the tube for guiding the reinforcing yarn 230, moved inward and upward out of normal action. A spring 233, operates to draw the arm 231, back when released from the action of the rocker arm 232, and this forward movement of the arm 231, will lay the reinforcing yarn across the finger 105^a extending from the main yarn feed loop so that the reinforcing yarn will be carried into the main yarn loop. The rocker arm 232, rests on the collar on the upper end of a rod 235. This rod 235, is connected at its lower end to a lever 236, 80 which is formed with a lug 237, adapted to coöperate with a pattern cam 238, mounted on the shaft 73, and rotating therewith. It will be readily seen that said cam 238, may be so shaped as to raise the lever 236, at 85 proper intervals to throw the reinforcing yarn feed out of action and that said lever may drop at proper intervals to allow the reinforcing yarn feed to move into action. 90 95 100

Pattern mechanism and operation of machine.

105

In order to control the clutch shifting drum, the belt shifting disk and the fashioning cam, I have provided a pattern chain 110 240, extending about idler wheels and engaging an operating sprocket wheel 241. This sprocket wheel 241, is integrally formed with a ratchet wheel 242. The ratchet wheel 242, is loosely mounted on the shaft 73. The ratchet wheel 242, is rotated on the shaft 73, by a pawl 243, which is pivoted on the stud 115 adjustably connected to the segmental gear 43. As the segmental gear is oscillated, continuously during the rotation of the main shaft, the pawl 243, will continuously rotate the ratchet wheel 242. The pattern chain is provided with a plurality of pattern lugs which are brought one after the other during the rotation of the ratchet wheel 120 125 into position to act upon a finger 245, which is rigidly connected to a rod 246, mounted in bearings in the machine. An arm 247, carried by the rod 246, is formed with a finger which engages a lug 248, on a collar 130

which is loosely mounted on the shaft 73. This collar carries an arm 249, to which is secured a pawl guard 250. The guard 250, coöperates with the wheel 75, already mentioned, which is rigidly secured to the shaft 73, by a set screw. This pawl guard extends above the teeth of the pawling wheel 75, for a certain distance. A second pawl 252, see Fig. X, is mounted on the stud carried by the segmental gear which supports the pawl 243, and the pawl 252, is for the purpose of pawling the wheel 75, and turning the shaft 73. This pawl 252, is normally held out of action with the teeth on the wheel 75, by the guard 250; when however, the pattern lug on the pattern chain engages the finger 245, and oscillates the same, the arm 249, will be turned thereby, which will move the guard about the outer surface of the ratchet wheel 75, and uncover the teeth thereof, to an extent depending upon the movement of the finger 245. A spring 255, normally holds the guard in its advanced position, covering the teeth of the ratchet wheel. As soon as a pattern lug passes the finger 245, the spring will throw the guard forward so as to throw the pawl 252, out of action. This guard 250, is rigidly attached to the arm 249, and lies alongside of the ratchet 75; when the pawl 252, rests thereon, it is held out of engagement with the teeth of the pawling ratchet wheel.

Starting with the pattern chain positioned as shown in the drawings, and the parts in operation for knitting the leg of the stocking, the pattern chain is traveling in the direction of the arrow in Fig. XIII. As soon as the lug 260, engages the finger 245, the guard will be shifted so as to uncover one of the small teeth of the ratchet wheel 75; as the pawl moves forward the ratchet wheel 75, will therefore be turned to the distance of one tooth. This turning of the ratchet wheel 75, will turn the shaft 73, and carry the fashioning cam one step which will change the position of the needle cylinder and thereby change the tightness of the knitted stitch. This occurs at the beginning of the ankle of the stocking. A further movement of the pattern chain will bring the pattern lugs 261, 262, 263, 264, and 265 in succession underneath the finger 245, moving the same so that the ratchet wheel 75, will be pawled one tooth thereby gradually shifting the fashioning cam and the production of the fashioning of the ankle of the stocking. During this movement of the shaft 73, the roller on the clutch shifting lever is moving in the straight portion 60 in the clutch drum. Also the belt shifting disk 88, is moving so as to bring the cam thereon into proper operative position relative to the lug 87. When the fashioning of the leg of the stocking is completed, then

the ankle is produced, and during this operation of the machine the pattern mechanism is idle. When the lug 266, is brought into proper position to move the finger 245, the ankle of the stocking is finished and the parts are to be positioned for the knitting of the heel pocket. This lug 266, is formed in two steps. The first lift of the pattern lug will uncover the medium length tooth in the ratchet wheel 75, and the pawl 252, will turn the pattern wheel and the shaft 73, through a certain distance. This movement of the shaft 73, will position the fashioning cam for the knitting of the heel pocket, which on the next movement will position the needle cylinder to produce the right tightness of the stitch. This shifting of the shaft 73, will bring into action the cam on the belt shifting disk, which will operate the belt shifter to change to slow speed, preparatory to the shifting of the clutch 80 and the oscillating of the needle cylinder. On the next stroke of the pawl which operates the ratchet wheel 242, a higher part of the pattern lug 266, will be brought into action, which will move the finger 245, a greater distance, and uncover one of the long teeth in the pawling ratchet wheel 75. The pawl 252, will now turn the ratchet wheel 75, through the distance of a long tooth, which is sufficient to move the shifting drum 95 to carry the roller on the shifting lever from one straight part of the cam groove to another straight part of the cam groove, which shifts the clutch and puts the parts in position for oscillating the needle cylinder.

This shifting of the clutch to oscillate the cylinder moves the bar 61, which throws into action, the raising cam for lifting the long butt needles to idle position, and releases the picker on the left of the machine, so that the same may be swung into operative position. This same movement of the bar 61, also withdraws the right hand end thereof from engagement with the lever which controls the widening picker and thereby positions the parts which control the widening picker, so that upon a later action, the same may be released, and the widening picker thrown into action.

A continuous movement of the pattern chain will bring the pattern lug 267, into action which will swing the finger 245, and allow the pawl 252, to turn the ratchet wheel 75, through the distance of a medium sized tooth. This movement of the shaft 73, will move the shifting drum so as to bring the pin on said shifting drum into contact with the lug on the lever which controls the widening cam. Upon the return movement of the segmental gear the hook arm will be engaged which will in turn release the latch holding the widening picker, out of action and allow the same to be thrown into.

- action for widening the heel pocket. This movement of the shaft 73, does not in any way affect the clutching operation or the fashioning cam. When the lug 268, is brought into action, the finger 245, will be swung far enough to uncover one of the large teeth of the ratchet wheel 75, and allow a sufficient turn of the ratchet wheel to move the clutch drum and shift the clutch lever to withdraw the reinforcing yarn and position the parts for circular knitting, for the formation of the foot of the stocking. This movement of the shaft 73, for shifting the clutch lever also rotates the disk for controlling the belt shifter, so as to shift the belt onto the high speed pulley and also rotates the fashioning cam so as to bring the proper finger controlling the position of the needle cylinder into action. The movement of the bar 61, which shifts the clutch will also cause the end of the bar to engage the lever which controls the widening picker and throw the same out of action.
- When the pattern lug 269, is reached the machine is positioned in precisely the same manner as through the action of the lug 266. The pattern lug 270, operates to throw in the widening picker in the same manner as the lug 267. The pattern lug 271, operates to position the parts for circular knitting in the same manner as the lug 268. At this point, the stocking is finished and a plurality of looper rounds are produced. The fashioning cam is also shifted at this time to bring the proper finger into action to position the cylinder for knitting the looper rounds. Upon the finishing of the looper rounds, the pattern lug 272, is brought into action, which will turn the fashioning cams and position the parts for the beginning of the knitting of the leg of the stocking. The pattern lug 273, is merely for the purpose of bringing the ratchet wheel 75, into the proper time relation for the operation of the fashioning of the leg of the stocking.
- The ratchet wheel 75, is formed as illustrated in the drawings, with an extra long tooth which while not performing any function in the present machine, may be useful for various other modified actions of the machine and with this extra tooth in the ratchet wheel this extra pattern lug is necessary to bring the parts into proper timing for action.
- It is obvious that minor changes in the details of construction and the arrangement of parts may be made without departing from the spirit of the invention as set forth in the appended claims.
- Having thus described my invention, I claim:
1. In combination, a needle cylinder and knitting cams; means for rotating one with relation to the other; a series of individually movable spring beard needles mounted in said cylinder; means for depressing the needle beards; means for laying the yarn against the needle shanks without sinking it between them before closure of the beards; and yarn supporting members arranged between the needles and having surfaces adapted to hold the yarn a sufficient distance above the previously formed fabric to allow the yarn to be passed by beards of the needles before they are closed by the action of the depressing means.
  2. In combination, a needle cylinder and knitting cams; means for rotating one with relation to the other; a series of individually movable spring beard needles mounted in said cylinder; means for depressing the needle beards; means for laying the yarn against the needle shanks without sinking it between them before closure of the beards; movable yarn supporting members arranged between the needles and having surfaces adapted to hold the yarn a sufficient distance above the previously formed fabric to allow the yarn to be passed by beards of the needles before they are closed by the action of the depressing means; and means for protruding and withdrawing said yarn supporters.
  3. In a knitting machine, the combination of a needle cylinder having spaced ribs forming needle slots, a series of needles mounted in said slots, fabric supporting members extending between the needles, a ring on which said members are mounted, means for attaching said ring to the upper end of the needle cylinder including a ring seated in the inner face of the supporting ring and engaging the ribs on the cylinder, and means for clamping the said ring against said ribs.
  4. In a knitting machine, the combination of a needle cylinder having a plurality of spaced ribs forming needle slots; needle jacks mounted in said needle slots, said jacks having operating butts, and being provided with stitch cams for engaging said butts; needles located in the needle slots and having their lower portions bent outwardly and downwardly to overlie the upper portions of the jacks, and having their lower extremities bent inwardly to engage said jacks; and flexible means for engaging the needles above the jacks, whereby said needles retain the upper ends of the jacks in place in the needle slots.
  5. In a knitting machine, the combination of a needle cylinder, having a plurality of spaced ribs forming needle slots, and needle jacks mounted in said needle slots and filling the space between said ribs, said jacks having operating butts, stitch cams for engaging said butts, spring beard needles located in the needle slots and having their lower portions bent outwardly and downwardly to overlie the upper portions of the jacks and

having their lower extremities bent inwardly to engage said jacks, flexible bands engaging the needles at points above the jacks, the upper ends of said jacks being held in place by the needles.

6. In a knitting machine, the combination of a needle cylinder having a plurality of spaced ribs forming needle slots, needles mounted in said slots, individual beard depressors mounted in the slots, means for operating the needles, a supporting ring attached to the upper end of the cylinder and surrounding said beard depressors, means for operating said beard depressors, fabric-supporting members carried by said supporting ring and extending between the needles, said beard depressors extending and operating between said fabric-supporting members, the upper and inner ends of said beard depressors being enlarged to fill the space between said fabric-supporting members.

7. In a knitting machine, the combination of a needle cylinder having a plurality of spaced ribs forming needle slots, needle jacks mounted in said slots and filling the space between said ribs, needles connected with said jacks, individual beard depressors mounted in the slots, means for operating the needle jacks, a supporting ring attached to the upper end of said cylinder and surrounding said beard depressors, means for operating said beard depressors, fabric supporting members carried by said supporting ring and extending between said needles, said beard depressors extending and operating between said fabric supporting members, the upper and inner ends of said beard depressors being enlarged to fill the space between said fabric supporting members.

8. In a knitting machine, the combination of a needle cylinder, a series of spring beard needles carried thereby and having their hook ends shaped to allow the yarn to freely reeve through the same, beard depressors for said needles, fabric-supporting members movable independently of said carrier and extending between the needles, means for moving the needles independently in succession below the fabric-supporting members to a predetermined extent to provide yarn for the fabric loops, a yarn-feeding device and stitch cams for the needles, said yarn-feeding device and stitch cams being so located that the knitting point is in advance of the tangential point of a line passing through the yarn feed, whereby the curve of the needle cylinder holds the yarn pressed against the shanks of the needles.

9. In a knitting machine, the combination of a needle cylinder, a series of spring beard needles carried thereby and having their hook ends shaped to allow the yarn to freely reeve through the same, beard depressors for said needles, fabric-supporting mem-

bers movable independently of said carrier and extending between the needles, means for moving the needles independently in succession below the fabric-supporting members to a predetermined extent to provide yarn for the fabric loops, a yarn-feeding device and stitch cams for the needles, said yarn-feeding device and stitch cams being so located that the knitting point is in advance of the tangential point of a line passing through the yarn feed, whereby the curve of the needle cylinder holds the yarn pressed against the shanks of the needles, said fabric-supporting members having an upper surface positioned to prevent the downward movement of the yarn with the needles and to force the same beneath the beards of the needles.

10. In a knitting machine, the combination of a needle cylinder, a series of spring beard needles carried thereby and having their hook ends shaped to allow the yarn to freely reeve through the same, beard depressors for said needles, fabric-supporting members movable independently of said carrier and extending between the needles, means for moving the needles independently in succession below the fabric-supporting members to a predetermined extent to provide yarn for the fabric loops, a yarn-feeding device and stitch cams for the needles, said yarn feeding device and stitch cams being so located that the knitting point is in advance of the tangential point of a line passing through the yarn feed, whereby the curve of the needle cylinder holds the yarn pressed against the shanks of the needles, each of said fabric-supporting members having a surface at an angle to but nearly parallel with, the fabric-supporting surface, for preventing the downward movement of the yarn with the needles and forcing the same beneath the beards of the needles.

11. In a knitting machine, the combination of a needle cylinder, a series of spring beard needles carried thereby, stitch cams for operating said needles, a yarn feeding device, said yarn feeding device and stitch cams being so located that the knitting point is in advance of the tangential point of a line passing through the yarn feed, whereby the curve of the needle cylinder holds the yarn pressed against the shanks of the needles, individual yarn supporters movable independently of the needle cylinder and extending between the needles for holding the yarn and forcing the same beneath the beard of the needle.

12. In a knitting machine, the combination of a needle cylinder, a series of spring beard needles carried thereby, stitch cams for operating said needles, a yarn feeding device, said yarn feeding device and stitch cams being so located that the knitting point is in advance of the tangential point of a

- line passing through the yarn feed whereby the curve of the needle cylinder holds the yarn pressed against the shanks of the needles, individual vertically moving beard 5 depressors and means for operating the beard depressors to close the beard after the free end of the beard passes the yarn. 13. In a knitting machine, the combination of a needle cylinder, a series of spring 10 beard needles carried thereby, stitch cams for operating said needles, a yarn feeding device, said yarn feeding device and stitch cams being so located that the knitting point is in advance of the tangential point of a line passing through the yarn feed, whereby the curve of the needle cylinder holds the 15 yarn pressed against the shanks of the needles, individual fabric supporting members movable independently of the needle cylinder and extending between the needles, each of said fabric supporting members having a projecting yarn supporter for preventing the downward movement of the 20 yarn with the needle and forcing the same beneath the beard of the needle, individual 25 vertically moving beard depressors, and means for operating the beard depressors to close the beards after the free end of said beard passes the yarn. 30 14. In a knitting machine, the combination of a needle cylinder, a series of spring beard needles carried thereby, stitch cams for operating said needles, a yarn feeding device, said yarn feeding device and stitch 35 cams being so located that the knitting point is in advance of the tangential point of a line passing through the yarn feed, whereby the curve of the needle cylinder holds the 40 yarn pressed against the shanks of the needles, individual fabric supporting members extending between the needles, each of said fabric supporting members having an upper surface positioned to prevent the 45 downward movement of the yarn with the needle and to force the same beneath the beard of the needle, and beard depressors for engaging and depressing the beard of the needle after the same passes the yarn on the yarn supporter. 50 15. In a knitting machine, the combination of a needle cylinder, a series of spring beard needles carried thereby, stitch cams for operating said needles, a yarn-feeding device, said yarn-feeding device and stitch 55 cams being so located that the knitting point is in advance of the tangential point of a line passing through the yarn feed, whereby the curve of the needle cylinder holds the 60 yarn pressed against the shanks of the needles, individual fabric-supporting members extending between the needles, each of said fabric-supporting members having a surface at an angle to but nearly parallel with the fabric-supporting surface to prevent the 65 downward movement of the yarn with the 70 needle and to force the same beneath the beard of the needle, and beard depressors for engaging and depressing the beards of the needle after the same have passed the yarn on the yarn-supporters. 16. In a knitting machine, the combination of a needle cylinder, a series of spring beard needles carried thereby, stitch cams for operating said needles, a yarn feeding device, said yarn feeding device and stitch 75 cams being so located that the knitting point is in advance of the tangential point of a line passing through the yarn feed, whereby the curve of the needle cylinder holds the 80 yarn pressed against the shanks of the needles, individual fabric supporting members extending between the needles, each of said fabric supporting members having a projecting yarn supporter for preventing the downward movement of the yarn with 85 the needle and forcing the same into the beard of the needle, and individual vertically moving beard depressors for engaging and depressing the beard after the same passes the yarn on the yarn supporter. 90 17. In a knitting machine, the combination of a needle carrier, a series of spring beard needles carried thereby, beard depressors therefor, a yarn feed, stitch cams for the needles, said yarn feed and stitch 95 cams being so disposed that the yarn is laid against the shanks of the needles, yarn supporters for each needle, and means for moving the yarn supporters between the needles, whereby the supporters are placed so that 100 the yarn is supported on the shanks of the needles without being crimped about the same, and positively forced beneath the beards of the needles, and said yarn is subsequently released by the withdrawing of 105 the supporters. 18. In a knitting machine, the combination of a needle cylinder, a series of spring beard needles carried thereby, beard depressors therefor, stitch cams for operating 110 the needles, a yarn feed, said stitch cams and yarn feed being so disposed that the yarn is laid against the shanks of the needles, yarn supporters for each needle, means for moving the yarn supporters radially of the cylinder, whereby said yarn supporters are placed so that the yarn is held on the shanks of the needles without being crimped about the same and positively forced beneath the beards of the needles, said yarn being subsequently released by withdrawing the supporters. 115 19. In a knitting machine, the combination of a needle cylinder, a series of spring beard needles carried thereby, beard depressors therefor, stitch cams for operating 120 said needles, a yarn feed, said stitch cams and yarn feed being so disposed that the yarn leading from the feed to the knitting point is pressed against the shanks of the 130

needles, yarn supporters for each needle, means for moving said yarn supporters radially of the cylinder whereby the yarn supporters are placed so that the yarn is 5 supported on the shank of the needle and positively forced beneath the beard of the needle and said yarn is subsequently released by the withdrawing of the supporter, said yarn supporters having an inclined 10 face so positioned relative to the needle that the tension on the thread draws the yarn down said inclined face toward the shank of the needle.

20. In a knitting machine, the combination of a needle cylinder, a series of spring 15 beard needles carried thereby, beard depressors therefor, stitch cams for operating said needles, a yarn feed, said stitch cams and yarn feed being so disposed that the 20 yarn leading from the feed to the knitting point is pressed against the shanks of the needles, yarn supporters for each needle, means for moving said yarn supporters radially of the cylinder whereby the yarn 25 supporters are placed so that the yarn is supported on the shank of the needle and positively forced beneath the beard of the needle and said yarn is subsequently released by the withdrawing of the supporter, 30 said yarn supporters having their forward ends inclined downwardly and so disposed that in the successive retracted positions between the yarn feed and the knitting point a V-shaped guiding channel is formed, 35 whereby the yarn extends in substantially a straight line from the knitting point to the yarn feed.

21. In a knitting machine, the combination of a needle cylinder, a series of spring 40 beard needles carried thereby, beard depressors therefor, stitch cams for operating said needles, a yarn feed, said stitch cams and yarn feed being so disposed that the 45 yarn leading from the feed to the knitting point is pressed against the shanks of the needles, yarn supporters for each needle, means for moving said yarn supporters radially of the cylinder whereby the yarn supporters are placed so that the yarn is 50 supported on the shank of the needle and positively forced beneath the beard of the needle and said yarn is subsequently released by the withdrawing of the supporters, the forward end of each yarn supporter being 55 inclined downwardly whereby the yarn carried thereby is forced downward toward the shank of the needle, and means for adjusting the working position of the yarn supporters to vary the position between the 60 point where the yarn passes underneath the beard of the needle and the point where the beard of the needle is closed.

22. In a knitting machine, the combination of a needle cylinder; a series of spring 65 beard needles carried thereby; means for

laying the yarn against the needle shanks without sinking it between them before closure of the beards; yarn supporting members extending between the needles; and means for depressing the beards of the needles, said yarn supporting members having the 70 yarn supporting surface downwardly inclined toward the needle, whereby the yarn is directed toward the shank of the needle. 75

23. In a knitting machine, the combination of a needle cylinder; a series of spring beard needles carried thereby; means for laying the yarn against the needle shanks without sinking it between them before closure 80 of the beards; fabric-supporting members extending between the needles; means for moving the needles in succession below a surface upon the fabric-supporting member to provide yarn for the fabric loops; 85 beard depressors; a yarn feed; yarn supporting members having at their inner ends a downwardly inclined surface adapted to force the yarn positively beneath the beards of the needles; and means for adjusting the 90 working position of said yarn-supporting members whereby the point of insertion of the yarn beneath the beard of the needle may be varied.

24. In a knitting machine, the combination of a needle cylinder; a series of spring 95 beard needles carried thereby; fabric-supporting members extending between the needles, each of said fabric-supporting members having a projecting yarn supporter 100 adapted to hold the yarn against the needle shanks without sinking it between the needles before closure of the beards; means for moving said fabric-supporting members radially of the cylinder; individual vertically 105 movable beard depressors for the respective needles; means for actuating said beard depressors; and means for moving the needles in succession below a supporting surface upon the fabric-supporting member to provide 110 yarn for the fabric loops.

25. In a knitting machine, the combination of a needle cylinder, a series of spring 115 beard needles carried thereby and having their hook ends shaped to allow the yarn to freely reeve through the same, fabric supporting members, extending between the needles, each of said fabric supporting members having a projecting yarn supporter, means for moving said fabric supporting 120 members radially of the cylinder, individual vertically movable beard depressors operating between said fabric supporting members, means for moving said beard depressors, stitch cams and a yarn feed, said stitch cams and yarn feed being so disposed that the 125 yarn extending from the knitting point is pressed against the shank of the needles and on to said yarn supporters whereby the same is positively forced beneath the beard of the 130

needle prior to the closing of the same by the beard depressor.

26. In a knitting machine, the combination of a needle cylinder, a series of spring beard needles carried thereby and having the hook ends shaped so as to allow the yarn to reeve freely through the same, means to press the beards, fabric supporting members movable independently of the needle cylinder and extending between the needles, means for moving the needles in succession below the fabric supporting members to provide yarn for the fabric loops, a normally stationary yarn feed, individual yarn supporting members between said yarn feed and the knitting point for supporting the yarn and forcing the same beneath the beards of the needles, said yarn supporting members being shaped so as to support the 10 yarn without bending the same between the needles.

27. In a knitting machine, the combination of a needle cylinder, a series of spring beard needles carried thereby and having the hook ends shaped so as to allow the yarn to reeve freely through the same, certain of said needles being capable of being moved to idle position, fabric supporting members extending between the needles, means for moving the needles in succession below the fabric supporting members to provide yarn for the fabric loops, a normally stationary yarn feed, individual yarn supporting members between said yarn feed and the knitting point for supporting the yarn and forcing the same beneath the beards of the needles, said yarn supporting members being shaped so as to support the yarn without bending the same between the needles, means for moving said yarn supporting members radially of the cylinder, and means for withdrawing said yarn supporting members from between the needles at a point in front of the yarn feed to prevent the interlocking 40 of the yarn with the yarn supporter between the first two idle needles upon reverse movements of the cylinder.

28. In a knitting machine, the combination of a needle cylinder, a series of needles carried thereby, fabric-supporting members carried by the cylinder, means for moving the needles in succession below the fabric-supporting members to provide yarn for the fabric loops, a bed on which said cylinder is supported, a standard carrying said bed, bearings in which said standard is movable, an arm having a stud engaging a cam face on a collar carried by the standard, whereby the oscillations of the arm serve to raise and lower the cylinder bed, and a pattern cam for oscillating the arm, said pattern cam having a plurality of cam faces and a plurality of fingers movable with the arm and coöperating respectively with said cam faces.

29. In a knitting machine, the combina-

tion of a needle cylinder, a series of spring beard needles carried thereby and having the hook ends shaped to allow the yarn to freely reeve through the same, fabric supporting members carried by the cylinder, means for moving the needles in succession below the fabric supporting members to provide yarn for the fabric loops, a bed on which said cylinder is rotatably mounted, a standard carrying said bed, bearings in which said standard is movable, an arm having a stud engaging a cam face on a collar carried by said standard, whereby the oscillations of the arm serve to raise and lower the cylinder bed, a pattern cam for oscillating said arm, said pattern cam having a plurality of cam faces and a plurality of fingers movable with the arm and coöperating respectively with said cam faces.

30. In a knitting machine, the combination of a needle cylinder, a series of spring beard needles carried thereby and having the hook ends shaped to allow the yarn to reeve freely through the same, fabric supporting members carried by the cylinder, means for moving the needles in succession below the fabric supporting members, to provide yarn for the fabric loops, a bed on which said cylinder is rotatably mounted, a standard carrying said bed, bearings in which said standard is movable, an arm having a stud engaging a cam face on a collar carried by said standard whereby the oscillations of the arm serve to raise and lower the cylinder bed, a pattern cam for oscillating the arm, said pattern cam having a plurality of concentric ribs of the same height, each of which is formed with a cam surface, and a plurality of fingers movable with the arm and coöperating with said cam surfaces.

31. In a knitting machine, the combination of a needle cylinder, a series of spring beard needles carried thereby and having the hook ends shaped to allow the yarn to freely reeve through the same, fabric supporting members carried by the cylinder, means for moving the needles in succession below the fabric supporting members to provide yarn for the fabric loops, a bed on which said cylinder is rotatably mounted, a standard carrying said bed, bearings in which said standard is movable, an arm having a stud engaging a cam face on a collar carried by said standard whereby the oscillations of the arm serve to raise and lower the cylinder bed, a pattern cam for oscillating the arm, said pattern cam having a plurality of concentric ribs of the same height each of which is formed with a cam surface, a plurality of fingers movable with the arm and coöperating with said cam surfaces, and means for independently adjusting said fingers.

32. In a knitting machine, the combina-

tion of independently movable needles comprising two series, stitch cams, means to relatively rotate and oscillate said cams with respect to said needles, means to throw one 5 of said series of needles out of action, means to successively throw out of action the leading needles of the other series, and means to successively throw into action thereafter the leading needles at the same end 10 of said series, beginning with a needle leading in the same direction as the needle first thrown out of action.

33. In a knitting machine, the combination of a cam shaft, means to rotate and 15 oscillate the needle cylinder, said means including an oscillated sector, a narrowing picker, means actuated during the forward movement of said sector to throw the narrowing picker into action; a widening 20 picker, means to throw said widening picker into action, said means comprising a connection positioned by a cam on said cam shaft, and a part operated by said sector upon its backward stroke.

34. In a knitting machine, the combination of a needle cylinder, means to rotate and oscillate said needle cylinder, a widening picker, means for throwing said widening picker out of action when changing 30 from oscillating to rotating movement of the cylinder, means for locking said widening picker out of action and independent means for throwing said picker into action in proper timing with the oscillations of the 35 cylinder.

35. In a knitting machine, the combination of a needle cylinder, means to rotate and oscillate the needle cylinder, said means including an oscillating sector, a narrowing 40 picker, means actuating during the forward movement of the sector to throw the narrowing picker into operation, means to throw the widening picker into action, a latch for holding said widening picker in action, and 45 means for releasing said latch including a device adapted to be engaged and moved by the sector upon its backward stroke, and pattern controlled devices operated upon the forward movement of the sector for positioning the devices for releasing the latch 50 so as to be engaged by the sector on its backward stroke.

36. In a knitting machine, the combination of a supporting frame, a forwardly projecting shelf having an opening therethrough carried by the frame, a needle cylinder in line with the opening in the shelf, a series of needles supported by said cylinder, stitch cams, means for giving said 60 needles and stitch cams a relative rotating or oscillating movement, including a transverse shaft mounted in the frame in rear of the needle cylinder, and transmission mechanism including a rotating gear and an oscillating gear, the axis of the needle cylinder 65

70 being located in a vertical plane at right angles to the transverse shaft and passing centrally through the transmission mechanism between the oscillating gear and the rotating gear.

37. In a knitting machine, the combination of a supporting frame, a forwardly projecting shelf having an opening therethrough, a needle cylinder extending through the opening and carrying a series 75 of needles, a gear connected at the lower end of the needle cylinder, a bed on which said gear rests, means for raising and lowering said bed, a gear located in rear of the first named gear and slidingly engaging the 80 same, means for rotating and oscillating said gear meshing with the gear on the cylinder, said means including a transverse shaft located in rear of the cylinder, and transmission mechanism including a rotating gear and an oscillating gear, the axis 85 of the needle cylinder being located in a vertical plane at right angles to the transverse shaft and passing centrally through the transmission mechanism between the 90 oscillating gear and the rotating gear.

38. In a knitting machine, the combination of a needle cylinder, means for rotating or oscillating said needle cylinder including 95 a sleeve having a gear, a clutch pin carried by said sleeve, an oscillating pinion located at one end of said sleeve and having a socket to receive the clutch pin when shifted in one direction, a rotating pinion at the other end of said sleeve and having a socket to engage 100 said clutch pin when moved in the opposite direction, a lever for shifting said clutch pin, a shifting drum for oscillating said shifting lever, a pattern controlled operating ratchet for moving said shifting drum, 105 said shifting drum and said ratchet having laterally projecting lugs and an adjusting screw carried by one lug and bearing against the other, whereby the position of the drum relative to the ratchet may be shifted for 110 properly timing the operating parts.

39. In a knitting machine, the combination of a needle cylinder, means for operating the needle cylinder, needles carried thereby, means for operating said needles, and a pattern mechanism for controlling the operation of the needle cylinder and needles, including cams, a shaft for operating said cams, a ratchet wheel for operating said shaft, a pattern member for controlling 115 the movements of said ratchet wheel, a second ratchet wheel for operating said pattern member, a vibrating member, and devices carried by said vibrating member for moving one of said ratchet wheels upon a 120 movement of the vibrating member in one direction, and for moving the other ratchet wheel upon a movement of the vibrating member in the opposite direction.

40. A knitting machine including in com- 130

- bination, a needle cylinder, means for operating the needle cylinder, needles supported thereby, means for operating said needles, devices coöperating with said needles for knitting, and a pattern mechanism for controlling the means for operating the needle cylinder, and needles and said coöperating devices, said pattern mechanism including a plurality of cams, a shaft on 5 which said cams are mounted, a ratchet wheel for operating said shaft, a pattern chain for controlling the movements of said ratchet wheel, a second ratchet wheel for operating said pattern chain, an oscillating 10 segment, a pawl carried by said oscillating segment and engaging one of said ratchet wheels, a pawl carried by said oscillating segment and engaging the other ratchet wheel, said ratchet wheels being so disposed 15 that a movement of the oscillating segment in one direction moves one of said ratchet wheels, and a movement of the oscillating segment in the other direction, moves the other ratchet wheel.
- 20 41. In a knitting machine, the combination of a needle cylinder having a plurality of spaced ribs forming needle slots, spring beard needles, beard pressers for said needles, means for operating the needles, a supporting ring attached to the upper end 25 of the cylinder and supporting said beard pressers, fabric-supporting members carried by said supporting ring and extending between the needles, said beard pressers extending and operating between the fabric-supporting members, the upper and inner ends of said beard pressers being enlarged 30 to fill the space between the fabric-supporting members.
- 35 42. The combination in a knitting machine of spring beard needles having relatively wide hooks, means to lay the yarn against the shanks of the needles without sinking it between them, means to press the 40 needle beards, a series of independently movable web-holders having upper and lower surfaces, and means to move the needles independently to cause them to advance to take the yarn, to recede toward the 45 upper surface of the web holders to engage the yarn, and to recede beneath the level of the lower surface of the web holders to draw the taken yarn through a previous loop to 50 form a knit stitch, whereby the degree of recession of the needles determines the amount of yarn drawn by the needles to 55 form the knit loops.
- 60 43. In a knitting machine, independently movable spring beard needles having hooks through which the yarn may freely reeve, needle advancing and needle retracting cams, and means to lay a new yarn against the shanks of the advanced needles, without sinking it between the needles, means to 65 press the beards of the needles, instruments

intercalated among the needles and means to independently move said instruments with respect to the needles, said instruments having an upper and a lower surface, the latter surface serving to determine a plane 70 below which the sinker wales of the last knit course of loops upon the needles cannot be moved by the friction of the needle shanks, and with respect to which the new yarn is drawn off into loops by the successive recession of the hooks of the said needles. 75

44. In a knitting machine, the combination of a cam shaft, means to rotate and oscillate the needle cylinder, said means including an oscillated sector, a narrowing 80 picker, means actuated during the forward movement of said sector to throw the narrowing picker into action; a widening picker, means to throw said widening picker into action, said means comprising 85 a part operated by said sector upon its backward stroke.

45. In combination, a needle cylinder and knitting cams; means for oscillating one with relation to the other; a series of individually movable spring needles mounted in said cylinder; means for depressing the needle beards; means for laying the yarn against the needle shanks in either direction of oscillation without sinking it between them before closure of the beards; 90 and yarn supporting members arranged between the needles and having surfaces adapted to positively hold the yarn in proper relation to be passed by the beard 95 of the needles before they are closed.

46. In combination, a needle cylinder and knitting cams; means for oscillating one with relation to the other; a series of individually movable spring needles mounted 100 in said cylinder; means for depressing the needle beards; means for laying the yarn against the needle shanks in either direction of oscillation without sinking it between them before closure of the beards; 105 and yarn supporting members arranged between the needles and having surfaces adapted to positively hold the yarn in proper relation to be passed by the beard of the needles before they are closed; and 110 means, coöperating with the needles in their descending movement, whereby the length of the loops is determined. 115

47. In combination, a needle cylinder and knitting cams; means for oscillating one 120 with relation to the other; a series of individually movable spring needles mounted in said cylinder; means for depressing the needle beards; means for laying the yarn against the needle shanks in either direction of oscillation without sinking it between them before closure of the beards; 125 yarn supporting members arranged between the needles and having surfaces adapted to positively hold the yarn in proper rela- 130

tion to be passed by the beard of the needles before they are closed; and means for effecting relative movement of the needles and yarn supporters to cause the latter to assume yarn supporting position adjacent to the leading active needle before the closure of its beard and during the passage of the point thereof beyond the yarn, in proceeding toward the knitting point at each reciprocation.

48. In combination, a needle cylinder and knitting cams; means for oscillating one with relation to the other; a series of individually movable spring needles mounted in said cylinder; means for depressing the needle beards; means for laying the yarn against the needle shanks in either direction of oscillation without sinking it between them before closure of the beards; yarn supporting members arranged between the needles and having surfaces adapted to positively hold the yarn in proper relation to be passed by the beards of the needles before they are closed; means for effecting relative movement of the needles and yarn supporters to cause the latter to assume yarn supporting position before the closure of the needle beard and during the passage of the point thereof beyond the yarn, in proceeding toward the knitting point; and means for effecting relative movement of the needles and yarn supporters in a radial direction at the region of the knitting point, to an extent sufficient to permit yarn to be snapped off from the supporter by the descent of the needles, while still remaining in operative position to engage beneath the yarn leading from the selvage loop.

49. In combination, a needle cylinder and

knitting cams; means for oscillating one with relation to the other; a series of individually movable spring needles mounted in said cylinder; means for depressing the needle beards; means for laying the yarn against the needle shanks in either direction of oscillation without sinking it between them before closure of the beards; yarn supporting members arranged between the needles and having surfaces adapted to positively hold the yarn in proper relation to be passed by the beards of the needles before they are closed; means for effecting relative movement of the needles and yarn supporters to cause the latter to assume yarn supporting position before the closure of the needle beard and during the passage of the point thereof beyond the yarn, in proceeding toward the knitting point; means for effecting relative movement of the needles and yarn supporters in a radial direction at the region of the knitting point, to an extent sufficient to permit yarn to be snapped off from the supporter by the descent of the needles, while still remaining in operative position to engage beneath the yarn leading from the selvage loop; and means for effecting relative movement of the needles and yarn supporters to an extent sufficient to completely clear the needles at the region of the yarn feed.

In testimony whereof, I have hereunto signed my name at Philadelphia, Pennsylvania, this twelfth day of June, 1911.

ALBERT M. PIGEON.

Witnesses:

JAMES H. BELL,
E. L. FULLERTON.
